CLAIM

The ornamental design for a light fixture, as shown and described.

DESCRIPTION

FIG. 1 is a first perspective view of the new design for a light fixture;

FIG. 2 is an end view of the light fixture;

FIG. 3 is a side view of the light fixture

FIG. 4 is a top view looking down at the light fixture; and, FIG. 5 is a bottom view looking up at the light fixture.

The mounting structure for mounting the light fixture to a wall or ceiling are not shown and form no part of the claimed design. In some embodiments, the mounting structures may not be visible, for example they may be mounted behind a wall or ceiling or covered with a film.

The broken lines shown in the drawings illustrate portions of the light fixture that form no part of the claimed design.
